Atty's

UNITED STATES PATENT OFFICE.

WILLIAM CUNNINGHAM, OF WATSONTOWN, PENNSYLVANIA.

BOILER-FEEDER.

SPECIFICATION forming part of Letters Patent No. 297,572, dated April 29, 1884.

Application filed August 2, 1883. (No model.)

To all whom it may concern:

Be it known that I, WILLIAM CUNNINGHAM, a citizen of the United States, residing at Watsontown, in the county of Northumberland and State of Pennsylvania, have invented certain new and useful Improvements in Boiler-Feeders; and I do declare the following to be a full, clear, and exact description of the invention, such as will enable others skilled in the art to which it appertains to make and use the same, reference being had to the accompanying drawing, and to the letters and figures of reference marked thereon, which forms a part of this specification.

15 My invention relates to feed-water regulators for steam-boilers, and has for its object the provision of means whereby the surface of water in a boiler may be at all times maintained at a given level or point, said means 20 operating, when the water-level falls below such given point, to automatically set a feed-water pump in motion to supply the desired quantity of water to bring the surface back to said given point.

25 As is well known to those skilled in the art to which my invention appertains, great care and attention are necessary to keep a proper supply of water in a boiler, whereby either bursting of the boiler or the weakening and 30 straining of its joints is avoided. Again, when the water is allowed to get low in the boiler, the process of filling or feeding such boiler is attended with great risk, not only to the boiler, but also to the attendant or operator. My invention 35 provides means whereby the water may be maintained at a given level automatically and without any care and attention from the attendant.

To the accomplishment of this end my invention 40 consists in the construction, arrangement, and combination of the various parts of my improvement, and in their operation when in position or attached to a boiler, substantially as hereinafter described and claimed.

45 The drawing represents my invention attached to a steam-boiler, and is partly in section, to show the position of the pipes.

Referring to the drawing, A represents the boiler, mounted upon the furnace A', and provided with steam-dome A².

B represents a steam-pipe extending from

the boiler A to the cylinder N, hereinafter described, said cylinder being connected by a pipe, B', extending to the valve-chamber C' of a small engine, C, the piston-rod C² of which 55 extends to and is connected with the plunger of a feed-water pump, E.

E' represents the supply-pipe, extending from the pump E to the cylinder N, and pipe E² connects the cylinder to the boiler A, through 60 which water is supplied to the latter. The cylinder N is of sufficient length to connect with the steam-space and with the water near the bottom of the boiler where the water enters from the pump. A space is formed in the top of the 65 cylinder by connecting the pipe B to its side. The other end, b, of the pipe is turned downward, the object being to prevent water from entering the pipe and passing from thence into the steam-cylinder. Such entry and passage 70 of the water would especially take place when the water is in a boiling condition, the surface of the water at such time not being quiet. To the top of the cylinder I connect the pipe B', leading to the valve-chamber of the pump; 75 and it will be readily seen that any water that would pass over before the pump had stopped would fall in the cylinder N, thereby preventing the steam-cylinder from being filled with water. The pipe B' may be connected to the 80 side of the cylinder, as shown in dotted lines, with equal effect.

E' represents the supply-pipe of the pump E, and D the exhaust-pipe of the steam-cylinder C. The steam-cylinder C and pump-cylinder E are mounted upon and securely fastened to a frame, H, said frame resting upon a block, H'.

I do not limit myself to the exact form of steam-pump above described, as it is apparent 90 that any form of steam-pump can be used.

F and G represent by dotted lines the steam-pipe B entering the boiler-shell at different points, the former, F, entering the steam-dome A² at a point above the desired surface-line 95 of the water and passing thence downward, as shown at f, to said line. The latter, G, enters the boiler at a point below the water-line, and passes thence upward through the water above the same, its end being turned downward, as shown at g.

The operation of my invention is as follows:

The water being above the end of the pipe B, when said pipe is in either of the positions shown, operates to close said pipe against the entrance of steam; but assuming that the surface of the water by reason of making steam has fallen below the end of the pipe B, leaving such end exposed, then steam will enter the pipe and pass thence to the steam-cylinder C and set in motion the feed-pump E, whereby water will be drawn through the pipe E² and forced through the pipe E' into the boiler until the water again rises so near to the orifice of the pipe that, either by damp steam being taken or the full supply of steam being cut off, the action of the pump will be thereby slackened to such a degree as to just hold the water at that point in the boiler, and not to cause the pump to cease acting.

I do not limit myself to entering the pipe B at a particular point of the boiler, as it may enter above or below the water-line, it only being necessary that the end of the pipe be bent downwardly to prevent water from passing through said pipe to and into the steam-cylinder C, as will be readily understood.

From the above-described construction it will be seen that my improvement affords a simple and reliable feed-water regulator for steam-boilers at a slight expense.

30 In the drawing I have designated the steam-pump formed by the combined steam-cylinder C and water-cylinder E by the general index letter M, that said pump may be readily referred to in the claims.

35 The cylinder N may be of glass or other suitable material, which cylinder is placed beside the boiler or at any desired distance therefrom, and connected to the boiler by pipes having the same relation to said boiler and its contained

40 water as the pipes B and E', said cylinder having pipes extending to and being connected with the steam-pump M, the ends of said pipes within the cylinder being disposed in the same manner, as at b in the drawing. By the con-

struction last above described the cylinder 45 may be used as a gage.

I am aware that it is not broadly new to provide a steam-boiler with a pipe extending downwardly therein to an established water-line, whereby steam may escape from the boiler 50 when the water falls below said line, thereby lowering a float and opening a valve to permit water to be supplied by a feed-pump.

I am also aware of a steam-pipe leading from the boiler to the pump, and upon the 55 water arising to a predetermined height it flows into the steam-pipe and stops the pump.

Having thus fully described my invention, what I claim, and desire to secure by Letters Patent, is—

1. In a device for feeding water to a boiler in which the steam-supply to the pump is regulated by the height of the water, the combination of a steam-pump, a boiler, a cylinder intervening between the boiler and pump, and 65 pipes connecting the cylinder with the boiler and pump, the cylinder having a steam-space in its upper part, said space being connected to the steam-space of the boiler by a pipe having its end bent downward, substantially as 70 shown and described.

2. In a boiler-feeder, the combination of the boiler, the cylinder N, the steam-pipes B and B', the first entering the cylinder in the side, and the other at the top, the first pipe being 75 bent downward in the steam-space of the boiler, the water-pipes E' E², and a steam-pump, whereby the boiler is fed automatically and water is prevented from entering the steam-cylinder of the pump, all substantially as shown 80 and described.

In testimony whereof I affix my signature in presence of two witnesses.

WILLIAM CUNNINGHAM.

Witnesses:

PHILIP SHAY,
WM. F. SHAY.
